DISPENSING CONTAINER

Lewis E. Kirkwood, Midland, Mich., assignor to The Dow Chemical Company, Midland, Mich., a corporation of Delaware

Filed Feb. 19, 1962, Ser. No. 173,978

6 Claims. (Cl. 229—51)

This invention generally relates to a dispensing container or carton for thin sheet material and, more particularly, relates to an improved dispensing container which makes use of a perforated and cut seam positioned in a novel manner such that the container can be readily opened by a pulling action.

It has been conventional in designing cartons for elongated rolls of thin sheet material, such as a roll of polymeric film, to use similarly elongated rectangular trunk-lid style folding cartons. A common disadvantage of such trunk-lid style cartons is the burdensome degree of difficulty the user experiences in attempting to open such a carton construction preparatory to using the product it contains. Where glue spots and perforations have been used previously, they have not allowed the carton to be correctly opened without a substantial measure of difficulty, or without tearing, maiming, or otherwise defacing the carton itself.

Accordingly, it is an object of the present invention to provide a trunk-lid style carton which may be readily and easily opened.

It is a further object of the present invention to provide a trunk-lid style carton which can be readily and easily opened upon application of pressure no matter how inaptly that pressure is applied.

Still another object of the present invention is to provide a novel perforated seam arrangement for trunk-lid style cartons which can be easily opened without tearing, maiming, or otherwise defacing the carton itself.

Briefly then, the present invention relates to a novel trunk-lid style carton wherein a perforated seam is formed between the front flange or face of a lid member and a front panel of the body of the carton such that insertion of fingers or other objects under the front flange of the lid results in an opening of the carton when a pulling pressure is applied.

Yet additional objects and advantages of the present invention, and its numerous cognate benefits and features are even more apparent and manifest in and by the ensuing description and specification taken in conjunction with the accompanying drawing in which wheresoever possible, like characters of reference designate corresponding material and parts throughout the several views thereof, in which:

FIGURE 1 is a plan view of a blank as cut, scored and perforated and from which a trunk-lid style container is formed;

FIGURE 2 is a top plan view, partially broken away, of a container formed from the blank of FIGURE 1, and including a roll of sheet film therein;

FIGURE 3 is a front elevational view, partially broken away, of the container of FIGURE 2;

FIGURE 4 is an end elevational view of the container shown in FIGURE 2;

FIGURE 5 is a cross-sectional view of the container of FIGURE 2 taken along the reference line 5—5 thereof; and

FIGURE 6 is a cross-sectional view similar to FIGURE 5, only taken after the lid member of the container is opened.

Blank 10 for a trunk-lid style container can be formed of any suitable material, as for example, paperboard, fiberboard, or any other container board material. Re-

2

ferring more particularly to FIGURE 1, box portion 12 of carton or container 14 (FIGURE 2) comprises a bottom panel 16 having joined thereto, along score line 18, a front panel 20 and, along another score line 18, a rear panel 22. Also connected to the bottom panel, front panel, and rear panel, are opposite end flaps 24, 26, and 28, respectively, for forming end panels 30 (FIGURES 2 and 4) of the container 14. These flaps are connected to their adjacent panels at additional score lines 18. A lid member 32 of the blank 10 is formed of a top panel 34 hingedly connected to rear panel 22 along yet another score line 18. Also forming parts of the lid member 32 are opposite side flanges 36 and front flange 38, each connected to top panel 34 along other score lines 18. Joined on opposite sides of front flange 38 are flaps 40 and elongated front flap 42, also joined by a score line 18.

In forming the container 14, front flap 42 is adapted to be reversely folded upon front flange 38 such that the perforated line 44 generally coincides with the portion illustrated by imaginary line 46 formed on the front flange. It is then the intent that the portions 48 and 50 of the front flap and front flange, respectively, be glued or otherwise secured together.

Container 14 is further assembled by folding along each of the remaining score lines 18 such that flaps 26 and 28 are glued or otherwise secured to the inside of the flap 24 and flaps 40 are glued to the inside of side flanges 36, with corresponding score lines coinciding. To complete the container 14, lip 52 of front flap 42 is brought into engagement with front panel 20 such that the surface of lip 52 opposite from that showing in FIGURE 1 is aligned with a portion 54 (defined by imaginary line 55) as indicated on front panel 20. The mating surfaces of lip 52 and portion 54 are then glued together to form a sealed carton as illustrated in FIGURES 2 to 5 described in more detail hereinafter. It is understood that in employing a tube style carton blank as illustrated in FIGURE 1 that the previously formed carton blank is normally erected by a machine (not shown and not forming a part of the present invention) which inserts the product or roll of film into the carton and then folds and glues the end flaps, this resulting in a complete package.

FIGURES 2 to 5 illustrate the complete carton 14 containing lid member 32, end panels 30, and body portion 12. Lid member 32 is illustrated as including a top rectangular panel 34 generally of the same, although somewhat larger, configuration as the body portion 12. Extending downwardly towards the bottom of the carton 14 are the opposite end flanges or sides 36 and front flange or side 38 of the lid member 32. Body portion 12 contains front panel 20, opposite end panels 30, bottom panel 16, and rear panel 22. Contained along the bottom panel 16 is a serrated knife blade 58 for use as a cutter blade for tearing film 60 from a roll 62.

Illustrated more clearly in FIGURES 3 and 5 is the novel arrangement of the present invention which renders efficient opening of the carton 14. As it can be seen, this arrangement is formed by gluing or otherwise securing the portion 48 of flap 42 to front flange 38, and by gluing or otherwise securing lip 52 of flap 42 to the upper portion 54 of front panel 20. Thus, perforated seam 44 can be easily opened by asserting a pulling force or pressure in an outwardly direction from the carton under the front flange 38 against portion 48 to separate the latter from lip 52. The tearing of perforated seam 44 can be accentuated by providing a substantial cut line 64 (FIGURE 1) along the seam if desired. Instead of having to push in to separate a perforated seam as is common in other devices, carton 14 of the present invention merely requires a pulling action or pressure which

is effective in opening the carton easily no matter how carelessly or otherwise inaptly the pressure is applied against seam 44. Since, in the finished carton, flap 42 is secured to front flange 38, a double thickness of material is present against which the pulling pressure can be applied. Maiming or other tearing of the carton will not generally occur if a construction similar to that discussed here is employed in a trunk-lid style carton. Furthermore, the securing of the subject components together in this manner results in a sealed trunk-lid style carton for its enclosed product from the time the product is packaged until it is opened by the ultimate consumer.

Carton 14, after it is opened, is illustrated in FIGURE 6 to show how the film 60 is removed therefrom. Obviously, it is brought out over the top of edge 66 on lip 52 15 and down around the blade 58 along which it can be readily torn after the desired quantity of film has been removed.

While certain representative embodiments and details have been shown for the purpose of illustrating the invention, it will be apparent to those skilled in the art that various changes and modifications can be made therein without departing from the spirit and scope of the invention.

Accordingly, what is claimed as new is:

1. A dispensing container comprising a hollow body portion including a front panel and a rear panel, a lid member hingedly attached to said rear panel and including a front flange overlapping said front panel, a reversely directed front flap extending from the bottom of said front flange, a lip forming an upper portion of said flap and being at least partially secured to the upper portion of said front panel, said lip separated from the rest of said flap by a perforated seam, whereby tearing of said perforated seam separates said lid member from said body portion for opening of the container.

2. The container of claim 1 wherein said lip is secured to said front panel with the upper extent of the former being above the upper extent of the latter.

3. The container of claim 1 wherein said seam includes an elongated cut-out portion.

4. The container of claim 1 wherein said flap and said front flange are secured together so as to form a double thickness to resist tearing upon the application of pressure.

5. A dispensing container comprising a box portion having a bottom panel, opposite end panels, a front panel and a rear panel, a lid member hingedly attached to said rear panel and including a top panel of the same general configuration as said bottom panel, opposite end and front flanges extending from said top panel towards the bottom of said box portion, said lid member being of a size such that said flanges slidably enclose the ends and front of said box portion, a reversely directed flap extending from the bottom of said lid member's front flange, a lip forming an upper portion of said flap and being at least partially secured to the upper portion of said front panel, said lip separated at least partially from the rest of said flap by a perforated seam, whereby said container can be opened by separating said lip member from said box portion along the seam.

6. A dispensing container comprising a hollow body portion including a front panel, a lid member fitting on said body portion and including a top panel having a front flange overlapping said front panel, a perforated seam at least partially along the length of said flange, a flap of said flange including at least said seam and a lip of the flange on the side of said seam most remote from the top panel being reversely folded, said lip being secured to said front panel such that access at least partially between said flange and said front panel is obtainable, whereupon pressure applied against said flange generally away from said front panel results in a separation of the lid member from the body portion along said seam.
